UNITED STATES PATENT OFFICE

NICOLAS EMILLEN METHLIN, OF PARIS, FRANCE, ASSIGNOR TO SCHNEIDER & CIE., OF PARIS, FRANCE, A LIMITED JOINT-STOCK COMPANY OF FRANCE

MECHANISM FOR AUTOMATICALLY OPENING AND CLOSING THE BREECH OF GUNS

Application filed September 25, 1930, Serial No. 484,396, and in France May 24, 1930.

This invention relates to improvements in the invention claimed in prior U. S. Letters Patent No. 1,731,863.

In this prior specification a mechanism has been described for automatically opening and closing the breech of guns, characterized by an abutment and guiding member for the breech operating lever, this member comprising an abutment and a sliding surface for the opening movements of the breech, connected to a bearing surface for holding the breech block in the open position during the end of the movement of return to battery position of the gun. The closure of the breech was effected automatically under the action of a spring stressed during the opening movement when the support of the lever on the guiding member was removed.

In the form of construction described and illustrated, the removal of this support was obtained by withdrawing the member laterally from the lever in order to permit the latter to rotate. The invention was applied by way of example to a breech with concentric screw threads, the operating lever being keyed upon the trunnion axis of the breech block.

The object of the present invention is to provide improvements in this automatic controlling mechanism.

The invention is described and illustrated as applied to a breech block with an eccentric screw, and in this particular application the mechanism for controlling the movements of the breech block is associated with a firing device which is also automatic. Means are also provided to permit the hand operation of the breech block and also of the firing.

The essential feature of the invention consists in principle in the means employed for removing the support of the breech operating lever on the member which guides the latter. For this purpose, instead of withdrawing laterally the arm or supporting bar on which the spring buffer of the operating lever slides, by pivoting at its front end, the said buffer is on the contrary withdrawn while the said supporting bar is allowed to remain fixed.

One form of construction of the invention

is illustrated by way of example in the accompanying drawings, in which:

Figure 1 is a longitudinal sectional elevation taken along the line 1—1 in Figure 2, showing the members in the closed breech position and arranged for automatic firing.

Figure 2 is a back elevation with a part in section taken along the line 2—2 in Figure 1, showing more particularly the transmission between the oscillating operating lever and the breech which has an eccentric screw.

Figure 3 is a horizontal section taken along the line 3—3 in Figure 1, showing in particular the firing members in the position for which firing has been effected.

Figure 4 is a sectional elevation of a part taken along the line 4—4 in Figure 3 and showing the shutter combined with the firing rack rod in a position preventing firing.

Figure 5 is a horizontal section taken along the line 5—5 in Figure 1, showing a detail of the shutter control.

Figure 6 is a view in sectional elevation similar to Figure 1, the members being shown in the open breech position.

Figure 7 is a back elevation with a part in section analogous to Figure 2, the section being taken along the line 7—7 in Figure 6.

Figure 8 is a plan view with a part in section taken along the line 8—8 in Figure 6 showing the device for withdrawing the spring buffer of the breech operating lever.

Figure 9 is a horizontal section corresponding to Figure 3 and showing the firing mechanism, the members of which are shown in the cocked position for firing a first shot.

Figure 10 is a sectional elevation of a part corresponding to Figure 1, the members shown being arranged in the practice position for which all automatic motions are thrown out of engagement.

Figure 11 is an external longitudinal elevation of the whole of the mechanism.

In these figures, A is the gun barrel and B the breech block which is here of the type having an eccentric screw thread. C is the oscillating breech operating lever which for the closing movements of the breech is controlled by a spring recuperator.

D is the cradle on which the gun barrel re-

coils E is the guiding arm similar to the guiding arm E in prior specification 1,731,863 but which, according to the present invention, is rigidly secured to the cradle and as in the said prior specification comprises a vertical core e and two horizontal fins e^1, e^2 the whole arrangement of which forms the guiding groove for the buffer of the hand grip upon recoil; this groove decreases gradually in depth from front to back. e^3 is the vertical abutment surface of the hand grip upon return to battery position.

The breech operating lever C is also provided with a spring grip C^0 comprising a buffer or pin C^1 constantly urged towards the axis of the barrel by a spring and adapted to run along the groove in the arm E when the barrel recoils, so as to abut against the vertical surface e^3 of the said arm upon the return to battery position, in order to cause the breech to open and then to slide on the horizontal surface e^1 . It is immediately seen that in order to close the breech after the return to battery position of the barrel, it is sufficient to push the spring pin C^1 inside its grip so as to make it escape from the support e^1 formed on the fixed arm E.

In the particular case envisaged, that is to say, the automatic control of a breech with an eccentric screw thread, the operating lever C is according to the invention, pivoted about a shaft c carried by a support A¹ rigid with the barrel A. The control of the operating lever C is effected as in the device according to the main patent by a recuperator comprising a cylinder H rigid with the barrel, and in which moves a piston I, a spring J being interposed between the end of the cylinder H and the piston I. The piston I is mounted at the end of a rod I¹, the back end of which is coupled by means of a link C² with a crank C³ rigid with the lever C. In this case, however, a diaphragm I² is placed between the piston I and the spring J; and in addition the piston and the diaphragm are guided longitudinally by tongues i^1 and i^2 respectively sliding in grooves h formed in the cylinder H.

According to the invention the rotation of the screw breech block is produced by the oscillation of the lever C by means of the following transmission. The screw breech block comprises a toothed sector B¹ which engages with a pinion K formed at the end of a sleeve K¹ which forms a nut for the rod of the piston of the recuperator I¹. The latter comprises a screw thread with a very long pitch, so as to permit the rotation of the sleeve nut K¹ to be obtained when the screw threaded rod I¹ moves longitudinally in one direction or the other. This sleeve nut comprises a collar on which are arranged ball thrust bearings K³ which engage on corresponding seatings on the recuperator cylinder H. The manner in which the opening and closing of the breech block B result from the longitu-

dinal displacements of the screw threaded rod I¹ will be immediately seen by an examination of Figures 1, 2, 6 and 7.

It has been shown above that the closing of the breech was obtained by the pivotal movement of the operating lever C under the action of the recuperator H, I, J when the lever was permitted to leave the arm E after the return to battery position of the barrel by the withdrawal of the pin C¹ of the said lever C.

The device for controlling the disengagement of the pin C¹ is formed according to the present invention, by a pin L¹ keyed upon the upper end of a rod L to the lower end of which is keyed a lever L² the free end of which is engaged in a recess formed in the back end of a horizontal rod M adapted to move longitudinally in bearings D¹, D² mounted on the cradle. At the forward end this rod comprises a shoulder M¹ the rear side of which bears against the bearing D¹, and a return spring N is placed in a lodgment formed in the bearing D¹ between the shoulder M¹ and a shoulder formed on this bearing. This spring N always tends to turn the rod M backwards and consequently to separate the pin L¹ from the pin C¹.

The forward end of the rod M is recessed to receive a spring piston M² serving as an elastic support for the lower end of a lever O¹ keyed upon a boss O which at its opposite end comprises a second lever O² the upper end of which engages in a slot P¹ formed at the rear end of a rod P.

The boss O, O¹, O² can turn about a fixed shaft D³ secured to the cradle D and a hand lever Q keyed to the outer end of this boss O enables the system of levers O¹, O² to be controlled. Naturally if it is not desired to combine the automatic breech controlling mechanism with the firing mechanism, the lever Q will only control the lever O¹ with a view to withdrawing the pin C¹, so as to permit the breech to be closed.

The rod P is the first member of a system of rodging for controlling the upward and downward movements of a shutter adapted to permit or prevent the expansion of the spring causing the firing to take place.

For this purpose the rod P is pivoted to one of the arms R of a bell crank lever R, R¹ mounted on a shaft D⁴ secured to the cradle D. The end of the arm R¹ is in its turn pivoted to the lower end of a vertical rod S the upper end of which acts on a lever T pivoted about a shaft D⁵ secured to the cradle D. The free end of the lever T penetrates into a recess formed at the base of a vertical shutter U sliding in a support D⁶ rigid with the cradle. The support D⁶ comprises an aperture d⁶ for the passage of the end of the firing rod and the shutter comprises an analogous aperture U¹ adapted to be made to correspond with the aperture d⁶.

It will immediately be seen that according as the shutter is in its lower position, as shown in Figure 1, or in its upper position, as shown in Figure 6, the firing rod can slide 5 forward or is stopped by the blank part of the shutter.

The vertical rod S is always urged upwards and consequently the shutter is also always urged upwards by a spring pusher s situated 10 in a lodgment formed at the base of the support D⁶ and which is always pressed by its spring against the lower end of the said rod S.

The transmission serving for producing 15 the firing operation is formed by a rod V rigid with a rack V¹ arranged near the rear face of the gun barrel and adapted to slide in supports a, a¹ carried by the latter.

The rear support a¹ serves as a guide and 20 abutment for the rod V which is constantly urged forward by a spring W interposed between the rear end of the lodgment formed in the support a¹ and a shoulder on the rod V.

The rack V¹ acts directly on the firing hammer X pivoted about a shaft carried by the gun barrel by means of its engagement with a small toothed sector x formed on the boss of the said hammer.

In order to produce the firing action, the 30 latter can strike a pusher b sliding in a lodgment formed at the back of the screw breech block B, this pusher transmitting the shocks it receives from the hammer to the striker b¹ through a lever b².

35 The control rodding of the shutter U which is actuated on the one hand by the hand lever Q comprises on the other hand a device permitting it to be automatically controlled by the screw threaded rod I¹ of the recuperator operating the breech lever.

40 For this purpose the forward end of the recuperator cylinder H comprises an axial casing H¹ in which a spring buffer Y the rear end of which is situated opposite the forward end of the screw threaded rod I¹ and can be pushed forward by the latter and the forward end of which is in contact for 45 automatic firing with a pin T¹ which may be keyed in two different angular positions 50 on the lever T operating the shutter U.

55 For this purpose the boss of the pin T¹ (Fig. 5) forms a lodgment for a helical spring which constantly presses it against the boss of the lever T. The latter comprises 60 for example two grooves arranged in suitable directions and in one or the other of which a pin engages which projects from the boss of the pin T¹. According as the pin is engaged in one or the other of the 65 grooves the pin T¹ occupies the position shown in Figures 1 and 6, or that shown in Figures 4 and 10, the firing rodding being thus actuated automatically or not actuated by the recuperator rod of the breech.

65 Finally the automatic breech controlling

mechanism may be put out of action temporarily, for example in order to facilitate practice manoeuvres, by locking the driving spring J of the spring recuperator in its compressed position.

70 For this purpose the recuperator cylinder H is provided with a locking pin Z pivoted about a shaft carried by the cylinder and which may be moved into an inoperative position (Figure 6) or into an operative position (Figure 10) by means of a spring grip z which can be engaged in the two positions in question. The wall of the cylinder H also comprises an aperture permitting the passage of the said locking pin Z which, when it occupies the position shown in Figure 10, is engaged in a catch formed on the diaphragm I² which is moved into the said position by hand operation.

75 It will immediately be seen that when the diaphragm is thus held in its rear position, the spring of the recuperator cannot possibly act on the piston I and when the breech lever is operated by hand the gun attendant does not have to exert the force necessary for compressing the spring.

80 The operation of the automatic breech mechanism, and of the firing mechanism when it is present, is as follows:—

85 When the members occupy the positions shown in Figures 1 to 3, the mechanism is arranged for the automatic control of the breech and the firing action, the breech being closed and the grip of the lever C having its pin C¹ engaged in the groove in the arm E.

90 If the barrel is assumed to be loaded in order to fire the first shot, the spring W of the firing rack V¹ must first of all be stressed by bringing the hammer by hand from the position shown in Figures 1 to 3 to that shown in Figures 6, 7 and 9. In this operation the rod V compresses the spring W and its end disengages from the apertures d⁶ and U¹ formed respectively in the support D⁶ and the shutter U.

95 As soon as the shutter has thus been released the transmission mechanism S—T actuated by the spring buffer s makes the shutter rise into the position shown in Figs. 6 and 9. This actuation of the said transmission S—T by the spring buffer s is permitted by the slot P¹ formed at the rear end of the rod P.

100 In order to fire the shot it is sufficient to move the hand lever Q from the intermediate position it occupies in Figure 1 to the extreme forward position, this movement having the object of removing the support of the rod V from the shutter U. In this pivoting movement of the lever Q forwards, the lever O¹ which makes the same angular displacement 105 simply compresses the spring buffer M² without exerting any action on the rod M which

then abuts by its collar M^1 against the end of its support D^1 .

The lever O^2 rigid with the hand lever Q pushes the rigging P forward which, by means of the rigging R^1-S-T moves the shutter U into its lower position, the aperture U^1 of the shutter being positioned in this way opposite the fixed aperture d^6 of the support D^6 .

As soon as this result has been obtained, the rod V is acted upon by its spring W and is thrown forward and its rack V^1 actuates the hammer X which thus produces the firing action (Figures 1 to 3).

When the shot has been fired, the gun barrel by recoiling carries with it the breech recuperator $H-I$ and the firing rod V . During the recoil the breech lever C acts as in the form of construction described in the Patent No. 1,731,863, that is to say, its spring pin C^1 first travels along the groove in the arm E and then leaves the latter before the end of the recoil.

As soon as the spring pin leaves the bore e of the arm under the action of its spring, it is driven towards the outside of the grip, so that when the return to battery position takes place, it can come into contact with the abutment surface e^3 .

During the return to battery position the pin C^1 encounters the vertical abutment surface e^3 which has the effect of making the lever C and the crank C^3 rigid with the latter pivot from front to back about the shaft c .

The crank C^3 in its movement carries along the rod I^1 of the recuperator and also the diaphragm I^2 and the piston I , the backward movement of which has the effect of stressing the spring J of the said recuperator.

Moreover, the longitudinal displacement of the screw threaded piston rod I^1 produces the rotation of the pinion sleeve K^1-K and consequently that of the screw breech block B by means of the toothed sector B^1 . The spent cartridge case is ejected after the pin has been lifted along the abutment surface e^3 and commences to slide on the surface e^1 .

At the end of the return to battery position of the barrel, the pin C^1 of the grip bears upon the upper surface of the arm E and it is situated opposite end in contact with the releasing finger L^1 , the breech being naturally open (Figure 6).

In order to continue firing, the gun is loaded by hand, for example, and the lever Q is then moved from front to back in order to produce the automatic closure of the breech and the consequent automatic firing of a shot.

This pivotal movement of the lever Q produces a pivotal movement of the same amplitude of each of the two levers O^1, O^2 . The rotation of the lever O^2 has no effect on the hammer action in view of the fact that this lever and the rod P are coupled together with the desired play by means of the slot P^1 .

The rotation of the lever O^1 produces the forward displacement of the rod M and consequently the pivotal movement of the lever L^2 the corresponding rotation of the rod L and of the finger L^1 which disengages the spring pin C^1 . As soon as the latter has left its support on arm E , the expansion of recuperator spring J moves the rod I^1 forward again, the effect of which is to make the breech lever C pivot from back to front.

The pin C^1 first slides upon the longitudinal outer face of the arm E ; it passes opposite the origin of the groove, mounts the lower wing e^2 by means of an incline e^4 (Figure 6) and then, continuing its circular movement, it engages at the front end of the said groove (Figure 2).

Towards the end of the power stroke of the recuperating piston I , the front end of the rod I^1 strikes the back end of the spring buffer Y , the axial movement of which causes the rotation of the finger T^1 and consequently that of the lever T which produces the downward movement of the shutter U .

As soon as the aperture U^1 becomes situated opposite the rod V the latter, under the action of its spring W , is thrown into the said catch A^1 and in its movement carries along the rack V^1 which actuates the firing mechanism as indicated above. The barrel recoils and the same cycle of operations is reproduced.

When it is desired to execute firing with the firing action hand operated and not necessarily following the operation of closing the breech, it is sufficient to disengage the transmission between the buffer Y and the rod T controlling the shutter U by simply lifting the finger T^1 out of the line of action of the said buffer Y as indicated above.

The finger T^1 then occupied the position shown in Figs. 4 and 10.

In this case the breech which has previously been closed, as shown above, by the displacement of the hand lever Q from its intermediate position to its back position in order to obtain the firing action at any moment, it is sufficient to lower the said lever Q into its forward position. The firing action is then produced as indicated for firing the first shot.

In order to effect practice manœuvres, for example, it is proper to employ the device for throwing the recuperator spring J out of action, shown in Fig. 10 and described above. In this case the breech is opened and closed by turning the breech lever C by hand, by means of its hand grip C^o .

Naturally the longitudinal displacements of the screw threaded rod I of the breech block recuperator are effected in the same way as when the breech was opened and closed automatically, so that the movements necessary for firing may follow the closure of the breech.

But the firing action may also be obtained as indicated above by moving the hand lever Q from the intermediate position to the forward position, the finger T¹ remaining then 5 in its raised position.

Claims:

1. In a mechanism for automatically opening and closing a gun breech, an operating lever, a guiding and supporting arm for said 10 operating lever, said arm being rigidly secured to the gun cradle and having a guiding surface for said lever during the movement of recoil of the gun, an abutment and sliding surface for the opening movement of the 15 breech, and a bearing surface for holding the breech in the open position during the latter portion of the movement of the gun in returning to battery, a pin carried by said lever and resiliently urged into engagement with said 20 surfaces, a spring normally tending to force said operating lever to a position to close the breech, means for compressing said spring when said breech is opened, and means for moving said pin out of engagement with said bearing surface to permit closure of the breech under the action of said spring.
2. In a gun, a rotatable breech block eccentrically threaded into the breech of said gun, a toothed sector formed on said breech block, a pinion engaging said sector, a threaded sleeve secured to and extending axially 30 of said pinion, a threaded rod engaging said threaded sleeve, means for preventing rotation of said rod, a breech operating lever operatively connected to said rod and pivotally mounted on said gun, means for automatically moving said lever about its pivot 35 during the counter-recoil movement of the gun and thereby rotating the breech block to open position, resilient means yieldingly resisting said movement of the lever, means for 40 maintaining said lever in breech open position, including a pin carried by said lever and a detaining surface engaged by said pin, and means for disengaging said pin from said 45 surface to permit closure of the breech under the action of said resilient means.
3. In a gun, a rotatable breech block eccentrically threaded into the breech of said gun, a toothed sector formed on said breech block, a pinion engaging said sector, a threaded sleeve secured to and extending axially 50 of said pinion, a threaded rod engaging said threaded sleeve, means for preventing rotation of said rod, a breech operating lever operatively connected to said rod and pivotally 55 mounted on said gun, a guiding and supporting arm for said operating lever, said arm being rigidly secured to the gun cradle and having a guiding surface for said 60 lever during the movement of recoil of the gun, an abutment and sliding surface

for the opening movements of the breech, and a bearing surface for holding the breech in the open position during the latter portion of the movement of the gun in returning to battery, a pin carried by said lever and resiliently urged into engagement with said surfaces, a spring normally tending to force said operating lever to a position to close the breech, means for compressing said spring when said breech is opened, and means for moving said pin out of engagement with said bearing surface to permit closure of the breech under the action of said spring. 70

4. In mechanism for opening and closing a gun breech of the type wherein a breech operating lever is automatically actuated by the counter-recoil movement of the gun to open the breech and is maintained in breech open position by the engagement of a pin carried by said lever with an abutment and guiding arm, means for disengaging said pin from said arm to allow said operating lever to be actuated for closing the breech comprising a shaft journaled in the gun cradle, a finger formed on said shaft and positioned 80 for movement into contact with said pin, a lever secured to said shaft, a rod having a cavity into which the free end of said lever extends, resilient means resisting longitudinal movement of said rod, and means for shifting said rod in opposition to said spring to rotate said shaft and finger comprising a hand-actuated lever and a one-way motion transmitting device operatively connecting said hand lever to said rod. 85

5. In a gun, a breech block, means for automatically opening said breech block by the movement of said gun in returning to battery, means for closing said breech block, means for firing the gun, and common controlling 90 means for said breech closing and firing means. 105

6. In a gun, a breech block, means for automatically opening said breech block by the movement of said gun in returning to battery, means for closing said breech block, and means actuated by said breech closing means for automatically firing said gun upon completion of the breech closing operation. 110

7. In a gun, the combination with means for closing the breech thereof, of means for controlling the firing action comprising a lever pivotally mounted on the gun cradle, a hand-actuated member for controlling the angular displacement of said lever, said member also controlling the actuation of the breech closing means, a firing hammer, means for actuating said hammer including a member supported by the gun barrel and longitudinally movable relative thereto, resilient 115 means tending to force said member in a direction to actuate said hammer to fire the gun, a shutter slidably mounted in the gun cradle in the line of movement of said longitudinally movable member and having an aper- 120 125 130

ture therein, said shutter preventing movement of said member to firing position except when said aperture is in registration therewith, transmission means operatively connecting said shutter and said lever, and resilient means normally urging said lever to a position wherein said shutter prevents movement of said member to firing position.

8. In the combination set forth in claim 7, means for automatically controlling the movement of said shutter comprising a lever forming part of said transmission means, a finger adapted to be clamped in a predetermined position with respect to said lever, means actuated by the breech closing means for automatically impacting said finger upon completion of the breech closing operation and thereby moving said lever to operate the shutter, and means for clamping said finger in a second position out of line of movement of said impacting means.

9. In mechanism for opening and closing a gun breech, a breech operating lever, means for automatically actuating said lever to open the breech by the movement of the gun in returning to battery, means for closing said breech including a spring which is compressed during the breech opening operation, and means for locking said spring in compressed position so that the breech may be opened by manually actuating said operating lever without the necessity for compressing the spring.

10. In mechanism for opening and closing a gun breech, a breech operating lever, means for automatically actuating said lever to open the breech by the movement of the gun in returning to battery, means for closing said breech including a diaphragm operatively connected to said operating lever and longitudinally movable in a casing carried by said gun, and a spring interposed between said diaphragm and said casing and adapted to be compressed during the breech opening operation, and means for locking said diaphragm in its position compressing said spring comprising a locking pin mounted on said casing normally out of engagement with but adapted to be moved into engagement with said diaphragm, and means for locking said pin in either engaged or disengaged position.

In testimony whereof I have signed this specification.

NICOLAS EMILIEN METHLIN.
